UNITED STATES PATENT OFFICE.

FRANK C. A. RICHARDSON, OF NEW YORK, N. Y.

DESIGN FOR A FINGER-RING.

51,763.

Specification for Design.

Patented Feb. 12, 1918.

Application filed July 26, 1917. Serial No. 182,983. Term of patent 3½ years.

To all whom it may concern:

Be it known that I, FRANK C. A. RICHARDSON, a citizen of the United States, and resident of the city, county, and State of New York, have invented a new, original, and ornamental Design for Finger-Rings, of which the following is a specification, reference being had to the accompanying drawings, forming a part thereof.

In the drawings I have shown in perspec-

tive a representation of a finger ring embodying my design.

The design comprises a finger ring of ornamental design. In the drawings a cover is shown, partly open.

I claim:

The ornamental design for a finger ring as shown.

FRANK C. A. RICHARDSON.
